UNITED STATES PATENT OFFICE

124,155

DESIGN FOR A DRESS

Anna Miller, New York, N. Y.

Application September 27, 1940, Serial No. 95,448

Term of patent 3½ years

To all whom it may concern:

Be it known that I, Anna Miller, a citizen of the United States, residing at 101 Central Park West, New York city, in the county of New York and State of New York, have invented a new, original, and ornamental Design for a Dress, of which the following is a specification, reference being had to the accompanying drawing, forming part thereof.

The trimming on the mock bolero and sleeves is comprised of large and small beads arranged in single and double rows as shown.

I claim:

The ornamental design for a dress, substantially as shown and described.

ANNA MILLER.
